J. Bateman.
Book Cutting.
N.Y. Patented Mar. 12, 1834.

Mar. 12. 1834

319.

D. S. B. Bateman
Glover's Patent

The Schedule referred to in these Letters Patent and making part of the same containing a description in the words of the said James Bateman himself of his improvement in the machine for cutting or trimming the edges of Books or Paper.

To all to whom these Presents shall come
Be it known that I. James Bateman of Harvard in the County of Worcester & Commonwealth of Massachusetts have invented a machine or a new & useful improvement in the art or business of cutting or trimming the edges of Books or paper & that the following is a fully exact description of the construction & operation of the said machine as invented & improved by me to wit. Said machine consists of three bars made of hard wood eight feet in length & six inches square placed perpendicularly one above the other the lower one resting on a bench or platform & confined thereto by bolts, nuts & screws. The upper bar is confined to the lower bar by plates of iron half an inch in thickness two inches wide & two feet in length placed on the outside of the bars near their ends and sunk their thickness into the bars & made fast by bolts & screws at a proper distance from the ends of said bars. this part of the machine is called the press. The middle bar called the follower plays up & down between the upper & lower bars with tenons at the ends so as to play between the plates of iron confining the upper & lower bars together. In the centre of the bars an half inch iron bolt passes through all the bars with a head at the bottom and fastened at top by a nut & screw to prevent the upper & lower bars from springing when in operation. On the middle bar at equal distances from the centre & ends are placed two iron plates fastened on with screws. The upper bar at corresponding distances with said plates pass two screws either wood or iron upon said plates, confined thereto by bolts with heads under side of the plates so as to move the said

the bar or follower up or down by turning the screws one way or the other. These screws serve to confine the books or paper between the lower & middle bars so as to be operated upon. Thus the upper & lower bars one inch from the ends project in an horizontal direction four three fourths inch iron bolts with an eye in each three fourths of an inch in diameter & screws cut in the eyes of the lower ones. Said bolts are confined on the opposite side of the bar with pins & screws. On the eyes of these bolts moves two turned iron perpendicular shafts with a screw cut six inches on the lower end & up to the lower bearings & corresponding with the screws cut in the eyes of the bolts. These shafts are two feet six inches in length. The lower bearings are three fourths of an inch in length & one inch & one half in diameter, the shafts are then turned down to three fourths of an inch in diameter & four inches in length to play in slits of the bar in which are confined the knives. The upper bearings of the shafts are five inches in length & one and one half inches in diameter the shafts are then to their tops turned to three fourths of an inch diameter. On the top of each shaft is a cross made of half an inch square iron with arms nine inch - is long & a right angled elbow nine inches from the centre six inches in length turned up on one of said arms. Said cross are riveted on to the shaft & move round with the shafts in an horizontal direction. On the upper bar on the side where said shafts are two other perpendicular shafts made of half inch iron fourteen inches long are attached to said bar nine inches distant from the centre of the large shafts by a screw passing thru said shafts & the centre of the bar. These shafts are flat where they come against the bar & round where they rise above the bar & so fastened by the screws as to admit of small longitudinal motion. The lower ends of these shafts are parallel with the under side of the bar & the form a right angled elbow turned towards the centre of the machine of an inch in length a small pin near the bottom of the bar prevents the bottoms of these shafts moving towards the centre of the machine.

chine. On the top of the upper bar & the same slide with the last described shafts are attached two steel springs nine inches in length upon a quarter circle & the tops resting against said last described shafts so as to intercept the motion of the crossed by coming in contact with the arms. On the upper bearings of the two large perpendicular shafts are attached cords passing horizontally to the opposite side onto a pulley & block & to the ends of said cords are attached weights which cause the pressure of the blades downwards when the machine is in operation. The bar which contains the knives is nine feet two inches long two and an half inches thick & four inches in depth with central perpendicular slits or mortises three fourths of an inch in width at each end said slits or mortises are a foot at one end & a foot & two inches at the other end. These slits play backwards & forwards upon the large perpendicular shafts & keep the bar containing the knives steady in its place when the machine is in motion. In the last mentioned bar or slide are fixed eight knobs made in the fashion of those commonly used placed at one foot distance from each other beginning one foot from the opposite end containing the wheel. The knives are dovetailed into the sockets with slits in the sockets up to the bar or slide. The sockets are let into the bar or slide on the side next the press so as to form an even surface & fastened by screws. In that part of the sockets with slits below the bar a small hole passes thro' one half & holds a screw in the other half so as to confine the knives tight in their places. On the upper part of the bar or slide containing the knives is an iron pin six inches long which by coming in contact with the lower end of the shafts fastened to the upper bar causes the upper part of said shafts against the springs towards the centre so as to permit the arms of the engine on the large shafts to pass which causes the bar containing the knives at eighteen inches distance from one end of the press two feet twelve inches in height with sockets for a weight to turn in sufficiently braced steadily to carry a cast iron wheel upon the weight three feet

feet in diameter & weighing over hundred pounds & runs partly in a massive cast iron. The bench or platform are erected on the side on which the crank is turned. It is so bent as to form a sweep of six inches to which a reach or fetch fastened to a bolt in the bar or side containing the knives also fastened by a socket. The crank is further so bent as to form another sweep of a foot at the handle to turn hold of to turn it. By means of the connexion of the reach or fetch with the shaft of the crank & the bar or side containing the knives to move in an horizontal direction alternately one foot each way at every revolution of the wheel & at each alternate movement the bar by means of the shafts & springs cords weights & screws is lowered & pressed down upon the book or paper to be cut or trimmed by the knives. These machines may be made on a larger or smaller scale than the one above described & with a greater or less number of knives & they may be operated with by manual, water or other power. The principles of this machine of which the said Jonas Batesman claims to be the inventor or discoverer are the simultaneous use of so many knives & brought to bear upon the books or paper to be cut or trimmed by turning the balance wheel & the consequent operation of the weights, shafts, screws & springs above described
